COMBINED PLANT AND CANDLE HOLDER

Le Roy J. Stangel, Box 502, Oconomowoc, Wis. 53066
Filed Dec. 10, 1975, Ser. No. 639,483

Term of patent 14 years

Int. Cl. D11—02; D26—01
U.S. Cl. D35—3 B

Fig. 1

Fig. 2

Fig. 3

FIG. 1 is a top plan view of a combined plant and candle holder showing my new design;

FIG. 2 is a front elevational view thereof;

FIG. 3 is a side elevational view taken from the right of FIG. 2.

I claim:

The ornamental design for a combined plant and candle holder, as shown.
